W. T. WAITE,
NOTE SHEET GUIDE FOR PIANO PLAYERS,
APPLICATION FILED AUG. 24, 1911.

Patented Jan. 13, 1914.

UNITED STATES PATENT OFFICE.

WILLIAM T. WAITE, OF KANSAS CITY, MISSOURI, ASSIGNEE, BY DIRECT AND MESNE ASSIGNMENTS, TO THE ORPHEOLA COMPANY, OF LAPORTE, INDIANA, A CORPORATION OF INDIANA.

NOTE-SHEET GUIDE FOR PIANO-PLAYERS.

1,084,568.

Specification of Letters Patent. Patented Jan. 18, 1914.

Application filed August 24, 1911. Serial No. 346,282.

To all whom it may concern:

Be it known that I, WILLIAM T. WAITE, a citizen of the United States, residing at Kansas City, in the county of Jackson and State of Missouri, have invented certain new and useful Improvements in Note-Sheet Guides for Piano-Players, of which the following is a specification.

This invention relates to note sheet guides for piano players, and it consists in the parts and combinations of parts hereinafter described and claimed.

The object of my invention is to provide means for tensioning the note sheet between the holding roll and the winding roll by the application of atmospheric pressure on the sheet at opposite sides of the note openings thereon, for the purpose of insuring unswerving travel of the note sheet and therefore guarding against the edges of the same becoming curled through contact with the end flanges of either roll.

A further object is to produce note sheet guides of simple and inexpensive construction which can be applied easily and cheaply to any of the approved piano players on the market.

Referring now to the accompanying drawing, forming part of this specification, and in which similar reference characters denote corresponding parts, Figure 1, is an elevation of a part of a piano player equipped with note sheet guide mechanism embodying my invention. Fig. 2, is an enlarged section taken on the line II-II of Fig. 1. Fig. 3, is a section taken on the line III-III of Fig. 2. Fig. 4, is a detail perspective view of one of the end guides. Fig. 5, is a detail perspective view of one of the vacuum chamber blocks.

In the said drawing, 1 and 2 indicate parts of the frame of a piano player of any suitable type, 3 the winding shaft, 4 the winding roll thereon and 5 the ends or flanges of the roll, these ends or flanges being ordinarily adjustable to accommodate note sheets of different width.

Adjacent to and parallel with shaft 3 is the tracker bar 6 of any suitable type, provided with the customary openings 7, the said bar being shown as extending from one part 2 to the other. At the opposite side of the tracker bar from the winding

roll are the customary alined sockets 8 and 9 for the reception of the customary stems 55 of the holding roll 10 for the note sheet 11 provided with the customary note openings 12.

Arranged between the tracker bar and the holding roll and preferably secured to the former near the extremity of the series of openings 7, are blocks 13 provided with vacuum chambers 14, and secured, in said blocks and communicating with said chambers are short tubes 15 two in one of said blocks and one in the other block to which are connected preferably a flexible tube 16 leading to the vacuum chamber (not shown) of the player the other tube 15 being joined by a flexible tube 16^a so that as long as the player is in operation the vacuum chambers will tend to produce a suction through chambers 14.

To provide an intermediate guide or friction surface for the note sheet between the tracker bar and the holding roll for substantially the full width of the sheet, a thin metal bar 17 extends from one block 13 to the other and across the faces of the same, and is provided with a pair of openings 18 in communication with chambers 14, this bar 17 being slightly curved so as to present a convex face to the note sheet, and to guard against injury to the latter the said bar 17 is curved back at its longitudinal margins at 19, the blocks being preferably grooved at 20 to receive the longitudinal edges of the said bar and thereby avoid the provision of any raw or sharp edges.

The vacuum chamber blocks 13 are provided in their outer sides with longitudinally extending holes 21, and each block is also provided with a threaded socket 22 wherein are secured set-screws 23 having annular grooves 24.

25 is a pair of end-guides for the blocks 13, provided with inwardly-projecting pins 26 to engage holes 21, and recesses 27 to fit snugly in the grooves 24 of set screws 23, and said end-guides are of such proportion 100 they project beyond the faces of blocks 13, as shown most clearly in Figs. 2 and 3. By turning the set screws 23 the end-guides can be adjusted toward or from the blocks 13 to dispose the inner faces of said guides in 105 the planes of the inner faces of the flanges

or ends of the rolls 4 and 10, as shown in Fig. 1, for the purpose of accommodating note sheets of varying widths.

In operation, the note sheet forms a closure for openings 18 of the bar 17 connecting the vacuum chamber blocks, so that the atmospheric pressure on the note sheet shall hold the latter frictionally against said bar and by thus tending to retard the travel of the note sheet, result in the tensioning of the same between said bar and the winding roll, so that the note sheet shall track perfectly upon the tracker bar without regard to whether the note sheet unwinds from the holding roll at a uniform speed or not, that is to say, without regard to whether slack occurs in the note sheet between the bar 17 and the holding roll. By thus tensioning the note sheet it is caused to travel in a direct line and swerves neither to the right nor to the left. It is thereby prevented from binding on the flanges of the winding roll and being curled or doubled over at its side margins.

25. In practice the movement of the note sheet is so accurate that the end-guides 25 really perform no function, the principal object of said guides being to guard against lateral or swerving movement when the note sheet is being rewound upon the holding roll, as at such time no vacuum is produced in the vacuum chamber blocks, though it is obvious that such purpose could be readily accomplished.

35. From the above description it will be apparent that I have produced a note sheet guide for piano players embodying the features of advantage enumerated as desirable and which is susceptible of modification in minor particulars without departing from the spirit and scope of the appended claims.

I claim:

1. The combination with a piano player having a tracker bar and a winding roll, of a note sheet holding roll, at the opposite side of the tracker bar from and parallel with the winding roll, and means for tensioning the note sheet between the winding roll and the holding roll, consisting of a friction surface for engagement by the note sheet near each side margin thereof and between the tracker bar and the holding roll, vacuum means arranged to exert a suctional action on the side margins of the note sheet to hold the same against said friction surface and tracker bar, and means for retaining said side margins under the action of said vacuum means throughout the travel of said sheet.

60. 2. The combination with a piano player having a tracker bar and a winding roll, of a note sheet holding roll at the opposite side of the tracker bar from and parallel with the winding roll, and means for tensioning the note sheet between the winding roll and

the holding roll consisting of a friction surface for engagement by the note sheet near each side margin thereof and between the tracker bar and the holding roll provided with vacuum chambers closed by the note sheet when traveling from the holding to the winding roll.

3. The combination with a piano player having a tracker bar and a winding roll, of a note sheet holding roll at the opposite side of the tracker bar from and parallel with the winding roll, and means for tensioning the note sheet between the winding roll and the holding roll consisting of a friction surface for engagement by the note sheet near each side margin thereof and between the tracker bar and the holding roll provided with an opening near each end, vacuum chamber blocks back of said friction surface and in communication with the openings of the latter, and suction tubes communicating with the vacuum chambers of said blocks.

4. The combination with a piano player having a tracker bar and a winding roll, of a note sheet holding roll at the opposite side of the tracker bar from and parallel with the winding roll, and means for tensioning the note sheet between the winding roll and the holding roll, consisting of a friction surface for engagement by the note sheet near each side margin thereof and between the tracker bar and the holding roll, means and vacuum means in communication with the under face of the sheet where it contacts with the friction surface, and end-guides at opposite ends of said friction surface projecting forwardly beyond the face of the same.

5. The combination with a piano player having a tracker bar and a winding roll, of a note sheet holding roll at the opposite side of the tracker bar from and parallel with the winding roll, and means for tensioning the note sheet between the winding roll and the holding roll, consisting of a friction surface for engagement by the note sheet near each side margin thereof and between the tracker bar and the holding roll, and means and vacuum means in communication with the under face of the sheet where it contacts with the friction surface, end-guides at opposite ends of said friction surface projecting forwardly beyond the face of the same, and means for securing the said end-guides against or slightly spaced from the extremities of said friction surface.

6. In a piano-player for use in conjunction with a perforated note sheet and provided with a tracker bar, a friction surface for engagement by and over which the perforated note sheet travels, provided with openings disposed in the path of travel of the side margins of the note sheet, a vacuum tube in communication with each of said

openings, and means for causing said side margins to close said openings throughout the travel of said sheet.

7. In a piano-player, a friction surface over which a perforated note sheet is adapted to travel and provided with openings always covered by the note sheet when in engagement with the friction surface, end-guides carried by and projecting beyond the face of the friction surface, and means for adjusting each end-guide sidewise toward or from the adjacent side margin of the note sheet.

8. In a piano-player, a friction surface over which a perforated note sheet is adapted to travel and provided with openings always covered by the note sheet when in engagement with the friction surface, end-guides carried by and projecting beyond the face of the friction surface, and each provided with a segmental recess in one edge, and suitably-supported adjusting screws, each provided with an annular groove receiving the recessed edge of a guide, so that turning movement of a screw shall impart lateral or sidewise movement to a guide to-

ward or from the adjacent side margin of the note sheet.

9. In a piano player, a tracker bar, a winding roll for drawing a note sheet across said bar, vacuum means in the path of travel of the side margins of the note sheet and adjacent the outer face of said bar, and means for maintaining said side margins subject to the suction of said vacuum means throughout the travel of said sheet.

10. In a piano player, a tracker bar, a winding roll for drawing a note sheet across said bar, and vacuum blocks in the path of travel of the side margins of the note sheet and adjacent the outer face of said bar, said blocks having openings closed by the passing note sheet, and means for retaining said side margins in position to close said openings throughout the travel of said sheet.

In testimony whereof I affix my signature, in the presence of two witnesses.

WILLIAM T. WAITE.
